UNITED STATES PATENT OFFICE.

CHARLES FREIHOFER, OF PHILADELPHIA, PENNSYLVANIA.

STEAM-BOILER FURNACE.

1,244,311.

Specification of Letters Patent. Patented Oct. 23, 1917.

Application filed March 3, 1915. Serial No. 11,766.

To all whom it may concern:

Be it known that I, CHARLES FREIHOFER, a citizen of the United States, residing in Philadelphia, Pennsylvania, have invented 5 certain Improvements in Steam-Boiler Furnaces, of which the following is a specification.

One object of my invention is to provide a novel construction and arrangement of 10 parts for use in connection with or as part of a plurality of steam boiler or other furnaces, whereby the discharge of smoke from the stack is effectually prevented, the invention 15 contemplating such a structure as will cause the combustible gases and smoke given off from a green fire in one furnace to be passed into or through a body of fuel which has been burning for some time in a second furnace, before being allowed to pass to the 20 stack.

Another object of the invention is to provide a novel arrangement of flues and dampers for use in connection with a plurality of 25 boiler furnaces whereby the gases and smoke given off from a freshly fired furnace may be caused to pass through a body of fuel in a furnace which has been fired for some time and whose products of combustion are led directly to a stack flue, the arrangement being 30 such that when the second furnace is fired its combustible gases and smoke are caused to pass through the fuel in the first furnace whose products of combustion are then delivered into the stack flue.

The invention also contemplates a novel 35 arrangement of flues and dampers for causing the gases passing from one furnace to be directed at will either directly into a stack or into a flue leading to another furnace.

These objects and other advantageous ends I secure as hereinafter set forth, reference 40 being had to the accompanying drawings in which,

Figure 1 is a vertical section of a steam 45 boiler constructed according to my invention;

Fig. 2 is a horizontal section on the line 46 a—a, Fig. 1;

Fig. 3 is a perspective view illustrating 50 the preferred arrangement of flues and dampers for controlling the flow of the gases between the furnaces of the boilers and between either of said furnaces and the stack 55 flue.

In the above drawings 1 represents a set-

ting which in the present instance is shown as provided with a vertical longitudinally extending partition 2 whereby it is divided into two independent chambers in each of 60 which are mounted the various parts constituting a complete steam boiler. While the detail construction and general design of these boiler units is immaterial, I have illustrated in the present instance boilers of the 65 water tube type each including a steam drum 3, a series of water tubes 4 and front and rear headers 5 and 6 whereby these tubes are connected to each other. As is common in the type of boiler shown, the front headers are connected to the front of the steam drum 3 while the rear headers are similarly connected through a suitable number of conduits 7 with the rear end of said drum. Each of the units likewise includes a mud 70 drum 8, a furnace 9, an ash pit 10 and baffle walls 11 and 12 whereby products of combustion from the furnace are compelled to circulate around the tubes before being delivered through an outlet opening indicated at 13 in one case and at 14 in the case of the second boiler, at the rear of the inclosing casing or setting.

According to my invention the outlet 13 of the boiler unit X has a continuation or 85 extension in the form of a chamber 15 communicating through an opening 16 with a stack flue 17 and through an opening 18 with the interior of a chamber 19 which in this case is immediately below it. Similarly 90 the outlet 14 of the boiler unit Y has an extension forming a chamber 20 connected through an opening 21 with the stack flue and through a second opening 22 with the chamber 19. This latter chamber is connected 95 through two substantially parallel conduits 23 and 24 with the ash pits 10 of the two boilers X and Y.

In the chamber 15 is mounted a damper 25, which in one position closes the opening 16 to the stack flue and in a position at right angles thereto closes the opening 18 to the chamber 19. A second damper 26 is likewise mounted in the chamber 20 in such manner that in one position it closes the 100 opening 21 and in its other position closes the opening 22. Within the chamber 19 are two dampers 27 and 28 whereby communication with the flues 23 and 24 may be opened or cut off at will. The pivot spindle 105 of the damper 25 has fixed to it an arm 29 which through a link 30 is connected to an

arm 31 on the pivot spindle of the damper 27 and these parts are so arranged that the latter damper is closed when the former damper is in a position to close the opening 5 16 to the stack flue, but is open when the damper 25 is so adjusted as to close the opening 18.

Likewise the pivot spindle of the damper 28 has fixed to it an arm 32 connected 10 through a link 33 with an arm 34 on a pivot spindle of the damper 26, and the arrangement is such that when said latter damper is in position to close the opening 22, the damper 28 is open, while when the damper 26 closes the opening 21, the damper 28 is closed. Through links 35 and 36 the two arms 29 and 34 are connected to the opposite extremities of a bar 37 fixed to a shaft or spindle 38 extended over the top of the 20 boiler to the front thereof and having fixed to its forward end a second bar 39 to whose extremities are connected operating cables 40 and 41.

Under conditions of operation the firing 25 of the boilers is so timed that when the unit X requires fuel, there is a clear fire in the furnace of the unit Y delivering its products of combustion without smoke to the chamber 20 and through the opening 21 into the stack flue 17, the damper 26 being in its lowered position closing the opening 22. When therefore the fresh fuel is delivered to the furnace 9 of the boiler X, there is produced a greater or less amount of smoke together 30 with certain unburnt gases which with the products of combustion, are delivered through the passage 13 into the chamber 15. By means of the cable 41, the bar 39, shaft 38, bar 37, link 36, and arm 29, the damper 35 40 25 is adjusted to the position shown which closes the opening 16, so that smoke and gases pass through the opening 18 into the chamber 19. The same operation which raises the damper 25, through the link 30 45 and arm 31 moves the damper 27 to its closed position, and also through the link 33 and arm 34 closes the damper 26 over the opening 22 and opens the damper 28. The smoke and other gases from the boiler X 50 therefore pass from the chamber 19, thence through the receiving flue 24 into the ash pit 10 of the boiler unit Y, and through the grate into the furnace 9. Here the smoke and gases are completely burned and the 55 final products of combustion from the boiler Y flow into the chamber 20, through the opening 21 into the stack flue 17.

When it is necessary to fire the furnace of the boiler Y, the cable 40 is drawn down- 60 wardly, thus swinging the arm 37 so that the openings 21 and 18 are closed while the entrance to the conduit 24 from the chamber 19 is closed and that to the conduit 23 is

opened. Smoke and unburnt gases from the fresh fuel supplied to the furnace of the 65 boiler Y are now delivered to the chamber 20 from whence they are forced to flow into the chamber 19, through the conduit or receiving flue 23 into the ash pit 10 of the boiler X, from whence they are forced through the 70 burning fuel of the furnace 9 belonging to this boiler where said gases with the solid particles constituting the smoke are completely burned. The products of combustion from this second boiler then flow 75 through the outlet 13 into the chamber 15 and through the opening 16 into the stack flue.

From the above description it will be evident that by firing the boilers alternately 80 and manipulating the dampers as noted, all gases arising from fresh fuel delivered to the furnace of either boiler are completely burned before they can possibly enter the stack flue, so that there is not only an added 85 economy due to this complete combustion but the discharge of smoke is effectually prevented.

I claim:—

1. The combination of two water tube 90 boilers each having a discharge flue at the back and a receiving flue extending forwardly from its back to its ash pit; a stack flue connected to said discharge flues; a chamber having openings to the under sides 95 of the discharge flues and also to the receiving flues; with dampers placed in the discharge flues respectively in positions for each of them to close either one of the openings to the stack flue or one of those to the 100 chamber; and other dampers for respectively cutting off the receiving flues from the chamber at will; with means for operating said dampers.

2. The combination of two boilers each 105 having a discharge flue and a receiving flue of which the latter is arranged to deliver gases to the furnace of its boiler; a stack flue connected to said discharge flues; a chamber mounted under the discharge flues and over 110 the rear ends of the receiving flues having openings to said discharge flues and also to the receiving flues; with oscillatory dampers placed in the discharge flues respectively in positions to close either one opening to the 115 stack flue or one to the chamber; other dampers for cutting off the flow from the chamber to the receiving flues at will; with means for operating the dampers.

In testimony whereof, I have signed my 120 name to this specification, in the presence of two subscribing witnesses.

CHARLES FREIHOFER.
